CLAIM

We claim an ornamental design for a bicycle lock, as shown and described.

DESCRIPTION

FIG. 1 is a perspective view of a bicycle lock of the new design;

FIG. 2 is a front elevational view of the bicycle lock of FIG. 1;

FIG. 3 is a rear elevational view of the bicycle lock of FIG. 1;

FIG. 4 is a left side plan view of the bicycle lock of FIG. 1; FIG. 5 is a right side plan view of the bicycle lock of FIG. 1;

FIG. 6 is a top plan view of the bicycle lock of FIG. 1;

FIG. 7 is a bottom plan view of the bicycle lock of FIG. 1;

FIG. 8 is a perspective view of another bicycle lock of the new design;

FIG. 9 is a front elevational view of the bicycle lock of FIG. 8;

FIG. 10 is a rear elevational view of the bicycle lock of FIG. 8;

FIG. 11 is a left side plan view of the bicycle lock of FIG. 8;

FIG. 12 is a right side plan view of the bicycle lock of FIG. 8;

FIG. 13 is a top plan view of the bicycle lock of FIG. 8; and,

FIG. 14 is a bottom plan view of the bicycle lock of FIG. 8. The broken line showing is included for the purpose of illustrating and forms no part of the claimed design.
